Patented Dec. 12, 1916.

UNITED STATES PATENT OFFICE.

CHAUNCEY E. RICHARDSON, OF CHEVY CHASE, MARYLAND.

SNAP-FASTENER.

1,208,010.

Specification of Letters Patent. Patented Dec. 12, 1916.

Application filed September 22, 1916. Serial No. 121,602.

To all whom it may concern:

Be it known that I, CHAUNCEY E. RICHARDSON, a citizen of the United States, residing at Chevy Chase, in the county of 5 Montgomery and State of Maryland, have invented certain new and useful Improvements in Snap-Fasteners, of which the following is a specification.

This invention relates to improvements in 10 snap fasteners, and it consists in constructions, combinations, and arrangements herein described and claimed.

The object of my invention is to provide an 15 improved snap fastener which will be doubly held in fastened or locked engagement, and which can be conveniently and easily fastened and unfastened under all practical conditions.

A further object is to provide an 20 improved snap fastener of more than the ordinary strength and durability by locking and interlocking the members thereof.

A still further object is to provide an improved snap fastener that can be affixed to 25 garments, gloves, curtains or other fabrics in such manner as to become a permanent fixture thereon, and not liable to cut the threads by which it is attached.

Another object is to provide an improved 30 snap fastener adapted to be readily fastened and unfastened without strain or injury to the materials to which it is attached, and with a minimum amount of physical effort.

Another object is to provide an improved 35 snap fastener in which the interlocking parts are shielded by a protecting casing or housing.

Another object is to provide an improved 40 snap fastener that is capable of attachment to fabrics in such a manner as to lend a certain rigidity or stiffness to the same, thus increasing the value of and making more effective the snap fastener as a closing device.

Another object is to provide an improved 45 snap fastener whose members cannot oscillate upon each other but will remain rigidly fixed in place when locked.

A still further object is to provide an improved 50 snap fastener which will exert its holding and closing influence over a larger area than is usually effected by snap fasteners.

In the accompanying drawings Figure 1 55 is a front face view of a primary socket

snap member, illustrating one embodiment of my invention; Fig. 2 is a longitudinal sectional view of the same; Fig. 3 is a front face view of the primary head snap member; Fig. 4 is a longitudinal sectional view 60 of the primary head snap member; Fig. 5 is a longitudinal sectional view of the members shown in Figs. 2 and 3, showing them in the act of being unfastened and released from locking engagement; Fig. 6 is a front 65 face view of a modification, the head and socket members being in locking engagement with each other; Fig. 7 represents a snap fastener with extended bases on either side of the locking members, and Fig. 8 shows 70 a snap fastener with its snap members and bases oval shaped.

Referring to the drawings 1 indicates the slightly elongated base of a socket snap member provided with a turned or round 75 edge 2, and apertures 8 for attachment, and having an upwardly projecting socket 3 slightly spaced from one end thereof, the projecting portion 4 of said base constituting a fulcrum for engagement by the interlocking member in unlocking the fastener. The walls of the socket 3 contain slots 14 80 and are shaped to provide reentrant snap members which converge inwardly from the walls of the socket at 5 and terminate in outwardly diverging portions 6, while 15 indicates an annular curved recess formed by a contraction of the lower part of the socket 3, for the reception of the corresponding curved contracted neck 16, at the lower part 90 of the casing or housing of the outer interlocking head member. The outer interlocking snap member is slightly larger than the socket snap member. It consists of a hollow 95 dome-shaped member 12, having a central downwardly projecting head 10, with a contracted neck 10^a and an extended base 7, with apertures 8 for fastening the base to a fabric. One portion 9, of said base is adapted to overlap the fulcrum 4 of the other member and is extended beyond the opposite side of the hollow member 12, to form a similar fulcrum 13. The head 10 is adapted for lockingly engaging the reentrant snap members of said socket member. 100

In Fig. 6 is illustrated a modification wherein the socket member, and the inclosing dome-shaped member, instead of being circular are of oval form. In other respects the construction of the two coöperat- 110

ing members of the fastener are the same as in the form illustrated in Figs. 1 to 5, inclusive, and the interlocking engagement of the parts is the same as in the latter construction. With the oval form of socket and inclosing dome-shaped member relative rotation of the two parts of the fastener on an axis passing vertically through the locking head 10, is prevented, and the fastener members are held in line one with the other. This is a desirable result where the fastener is used for securing together the parts of certain garments, where relative movement of the edges of the garment is not desired.

15 In the use of my invention the two halves of the device are, by their bases 1 and 7, attached to the fabric upon which they are to be used, the elongated portions of the bases of each being arranged on opposite 20 sides of the center thus formed, when in locked position. In operation, the head member is pressed against the socket member and the head 10 enters the inwardly converging portions 5 of the reentrant snap 25 members which latter yield sufficiently to permit insertion of the head therethrough into locking engagement with the outwardly diverging portions 6 of said members, said inwardly converging portions 5 acting to 30 center the head 10 and to insure the smooth easy entrance thereof into locked engagement with the parts 6. In conjunction therewith, the curved wall of the contracted neck 16 of the head member simultaneously 35 slips into the curved recess 15 of the socket member, lockingly engaging the socket member and constituting a second lock to render the locking thereof doubly rigid and secure.

40 To unfasten the device, a slight pressure upon the terminals of the elongated bases causes a swinging action upon the fulcrum 4 or upon the fulcrum 13, causing the bases 1 and 7 to act leverwise upon each other, resulting in the disengagement of the neck 16 45 from its seat 15 and the withdrawal of the head 10 from the socket snap member 3 thus promptly and effectively separating the two principal members from each other.

50 In showing the improved form of snap fastener with slightly elongated bases, I have not precluded the use of the ordinary round, or any other preferred shape of base or bases. Likewise in showing the oval construction of the upwardly projecting socket member 3 and the downwardly projecting head member 12, in Fig. 6, I have not restricted myself to that particular shape, but these members may be square, oval, diamond, or any desired shape that will prevent the members from turning upon each other laterally when in use.

55 In Fig. 7 portions of the bases 1^a, 1^a, and 7^a, 7^a, of the two fastener members are extended, for a suitable distance, upon opposite sides of each member, and if desired

said bases may be crossed when the members are assembled, as shown.

In the modification shown in Fig. 8, both the interlocking portions of the fastener members, and their bases, are of oval form.

70 The device may of course be attached to garments, gloves, shoes, storm curtains, etc., by rivets, clips, strips or points made thereon or applied thereto, or by any other means, within the scope of my invention, although 75 for convenience I have illustrated needle holes as a means for attaching.

I have illustrated and described preferred and satisfactory constructions, but changes could be made within the spirit of my invention.

80 Having thus described my invention what I claim as new and desire to secure by Letters Patent of the United States is:

1. A snap fastener member comprising a 85 base having a projecting socket portion provided with reentrant inwardly and outwardly curved snap members, in combination with a coöperating member comprising a base having a curved projecting portion 90 shaped to fit over said socket member and a depending head for locking engagement with said snap members, said socket and projecting portions having interlocking engagement at their bases.

95 2. A snap fastener member comprising a base with a raised socket thereon provided with a contracted neck and central reentrant inwardly and outwardly curved locking members, in combination with a second member comprising a base with a projecting portion thereon shaped to fit over said socket and having a contracted portion near the base, and a depending head, to interlock with said contracted neck and locking members, respectively.

100 3. A snap fastener member comprising an elongated base having a series of perforations near its edges and near one end having a projecting socket with central reentrant inwardly and outwardly curved locking tongues, in combination with a second member comprising an elongated base having a series of perforations near its edges and near one end a dome-shaped projection with a central depending head arranged to fit over said socket with said head in locking engagement with said tongues.

110 4. A snap fastener member comprising a base having a socket in combination with a second member comprising a base having a hollow portion to fit over and have locking engagement with the socket, said socket and hollow portion being shaped to prevent relative rotation of the fastener members.

115 5. A snap fastener member comprising a base having a projecting socket thereon, in combination with a second member comprising a base having a coöperating projecting hollow portion to fit over said socket, said

socket and hollow portion being of oval form to prevent relative rotation of the fastener members.

6. A fastener member comprising a base having a raised socket with reëntrant locking portions, and an annular recess near said base, in combination with a second fastener member comprising a base having a raised hollow portion to fit over the socket, a head 10 to engage said locking portions, and a contracted neck to fit said annular recess.

7. A snap fastener comprising a socket member provided with a projecting socket having reëntrant snap members converging 15 inwardly from the walls of said socket and terminating in outwardly diverging portions, said socket member provided with an encircling recess around or near its base, and a head member provided with a head 20 adapted for insertion through said snap members into locking engagement with said outwardly diverging portions of the latter; and provided with an encircling indentation around or near its base adapted for engagement with the corresponding recess near the 25 base of the socket member.

8. A snap fastener comprising a socket

member consisting of an elongated base having a projecting socket spaced slightly from one end thereof whereby one end constitutes 30 a fulcrum and the other end of said elongated base provides convenient means for readily unfastening the snap fastener, and a head member consisting of an elongated base having one end adapted to overlap said 35 fulcrum end of the socket member, and provided with a head for lockingly engaging said socket and with additional means for lockingly engaging the housing of said head member with the housing of the said socket 40 member, and the other end of said elongated base of the head member constituting convenient means for readily disengaging the snap fastener.

9. A snap fastener comprising a socket 45 member having reëntrant snap members, a head member provided with a head adapted for insertion through said snap members into locking engagement therewith, both socket and head members being 50 laterally oval and adapted to so engage each other as to maintain their relation to each other without turning upon a center.

CHAUNCEY E. RICHARDSON.
